UNITED STATES PATENT OFFICE.

EDWARD THOMAS CONNOR, OF ILLIOPOLIS, ILLINOIS.

DESIGN FOR A WASHER FOR NUT-LOCKS.

SPECIFICATION forming part of Design No. 28,951, dated June 28, 1898.

Application filed February 3, 1898. Serial No. 669,025. Term of patent 14 years.

To all whom it may concern:

Be it known that I, EDWARD THOMAS CONNOR, a citizen of the United States, residing at Illiopolis, in the county of Sangamon and State of Illinois, have invented and produced a new and original Design for a Washer for Nut-Locks, of which the following is a specification, reference being had to the accompanying drawings, forming part thereof.

Figure 1 is a face view of a washer constructed in accordance with my design, and Fig. 2 is a sectional view on the line 2 2 of Fig. 1.

As shown in the drawings, the leading or material feature of my design consists of a washer from the main body of which project four arms, as at A, B, C, and D, the main body of the washer without said arms being substantially rectangular and included within the points E, F, G, and H, a central circular opening I being made through the washer,

and a small portion of the main body, between the points H and the arm A, being curved on its periphery, as at J.

The arm A is formed to project at an inclination from a line drawn vertically through the washer, as illustrated in the drawings, said inclination being to the left, while the arms B, C, and D are projected on lines at angles of ninety degrees (90°) to each other.

A tooth A' projects laterally and upwardly from arm A near its outer end.

Having thus described my invention, what I claim as new, and desire to secure by Letters Patent, is—

The design for a washer for a nut-lock, as herein shown and described.

EDWARD THOMAS CONNOR.
